VICTOR C. GILPIN AND JOHN E. McAULIFFE, OF BROOKLYN, NEW YORK.

FABRIC CONDUIT.

Specification of Letters Patent. Patented June 22, 1920.

1,344,501.

Application filed April 13, 1918. Serial No. 228,487.

To all whom it may concern:

Be it known that we, VICTOR C. GILPIN and JOHN E. McAULIFFE, citizens of the United States of America, residing at Brooklyn, in the county of Kings and State of New York, have invented new and useful Improvements in Fabric Conduits, of which the following is a specification.

This invention relates to conduits for electric wires and has particular reference to that class of conduits which are composed of a tubular fabric of textile material, the same being impregnated with heat resisting water-proof material of some well known character that will not materially interfere with the flexibility of the conduit, permitting the same to be bent and otherwise manipulated to suit given requirements.

The object of the invention is to provide a knitted conduit in which use may be made of one or any suitable number of strands of yarn, interlooping the yarn so that loops with their broad bights will all be arranged upon the exterior of the conduit, while upon the interior thereof will be produced longitudinally extending rib like portions and longitudinal grooves between the rib portions so that the inside of the conduit will be of a smooth nature to permit the line wires to be fed therethrough without interruption.

We further provide a knitted conduit made up of interlooped portions in which broad bights of said loops will be arranged upon the outside of the conduit and in circular rows side by side, with the loops of one row extending in an opposite direction to the loops of the next two adjacent rows so that the conduit will be of a highly flexible character capable of being curved in any desired direction without fear of the walls collapsing and at the same time giving to the exterior of the conduit an arrangement which will afford excellent lodgment for an impregnating material or substance.

In practice, we find that a fabric constructed as described above possesses a relatively thick and heavy wall structure which, when properly produced, may be made sufficiently open and porous to permit thorough impregnation with water-proof and moisture repellent material in an easy and convenient and inexpensive manner. When impregnated, the fabric is rendered highly flexible, may be bent, twisted and otherwise manipulated without cracking, kinking, col-

lapsing or otherwise suffering injury that will interfere with the perfect utility thereof. These qualities are believed to be due not alone to the fact that the tubular fabric used in carrying out the invention possesses a heavy body, but also in a measure to the peculiar manner of looping the yarn to produce interior longitudinal ribs and grooves respectively and exterior rows of loops having substantially internested bight portions.

In the accompanying drawing has been illustrated a simple and preferred embodiment of the invention, it being, however, understood, in order that no limitation is necessarily made to the precise structural details therein exhibited but that changes, alterations, and modifications within the scope of the appended claims may be resorted to when desired.

In the drawing, Figure 1, is a view in side elevation of a piece of tubular textile fabric used in carrying out the present invention, the same being shown on an enlarged scale.

Fig. 2, is a transverse section therethrough taken on line 2—2, in Fig. 1.

Fig. 3, is a similar view illustrating the tubular fabric impregnated to form a conduit.

Fig. 4, is a side view of the fabric impregnated to form the conduit.

Corresponding parts in the several views of the drawing are denoted by like characters of reference.

The tubular fabric shown at A, is formed by a process of knitting from a single piece of yarn as shown at 15, or if desired, several strands of yarn may be used, the fabric being composed of interengaging or intermeshing loops 16. Tubes of proper dimensions for general use may be produced having nine loops in circumferential series, but the number of loops in each circumferential series may be greatly varied, in fact indefinitely so, within the scope of the present invention. By using yarn of sufficient thickness, a body of tubular fabric will be given a wall of ample thickness and by knitting the fabric more or less closely, the porosity of the wall portion may be gaged and regulated, rendering the same more or less absorbent and enabling it to be thoroughly impregnated with heat resisting and moisture repellent materials of various consistencies such as it may be found desirable to use. It will be noted by reference to Figs.

1 and 2, that the fabric of the conduit presents longitudinal interior ribs 17, each rib being formed of a longitudinal series of intermeshing loops, and the several ribs being spaced apart by interior V shaped grooves 18 (see Fig. 2), which ribs and grooves will be extremely definite owing mainly to the coarseness of the yarn employed in the manufacture of the tube. The V shaped grooves, owing to the general structural formation of the fabric may be regarded as extending longitudinally throughout the length of the conduit so that the interior of said conduit will be of a smooth nature. No obstructing surfaces will be presented on the inside of the conduit through this described formation and the longitudinal extending grooves 18, and the ribs 17, act as guiding surfaces over which the feed wires may be freely passed during the feeding or inserting of the same through the conduit.

The broad bights 19, of the mentioned loops 16, are all arranged exteriorly of the conduit and in substantially circular rows, with those of one row nested with those of the next two rows but projecting in an opposite direction therefrom as shown in Fig. 1. Through this arrangement the small interstices between the respective bights of said loops afford excellent lodgment for the impregnating material or substance and the latter, when applied will combine with the textile fabric to form a substantially homogeneous structure which should be of an insulating character as will be recognized by reference to Figs. 3 and 4, where the impregnated tubular fabric has been designated by B.

When an impregnated tube having characteristics herein shown and described is bent or twisted, the comparative looseness of the textile fabric taken in connection with the thickness of the wall portion will constitute a safeguard against kinking or collapsing. It is said that the freedom from danger of kinking or collapsing is also in a measure due to the interior rib and groove construction, the same giving longitudinal rigidity to the structure while permitting the same to be flexed very readily.

The features which we desire most particularly to emphasize are the exterior arrangement of the bights of the loops so as to give the maximum purchasing surface to the impregnating substance or material; arranging the loops in circular series, disposing the series side by side and causing the bights of one series to be projected in an opposite direction to the bights of the next two series and so on throughout in the structural formation of the conduit, and then arranging the respective interlooped portions of the fabric so that well defined longitudinal grooves and ribs respectively are formed in-

teriorly of the conduit throughout the length thereof, the latter giving perfect freedom to the insertion of the line wires therethrough. Were the arrangement the reverse of that shown and described, many obstructions would be present against the passage of the line wires and the conduit, commercially would not be as valuable and practical.

What is claimed as new is:

1. A tubular knitted conduit characterized by exterior loop bights, with the bights in one row about the conduit extending in an opposite direction to the bights in the next adjacent rows to render the conduit highly flexible, and also characterized by interior longitudinal rib-like portions with grooves between said rib-like portions at the inner side of the conduit; said rib-like portions being arranged in pairs and said pairs being straddled by some of said loops. 75

2. As a new article of manufacture, a fabric single walled conduit characterized by exterior annular rows of loop bights, with the bights in one row about the conduit extending in an opposite direction to the bights in the next adjacent rows to render the conduit highly flexible and provide radially extending interstices between all of said loops, said fabric also characterized by interior longitudinal rib-like portions with longitudinal grooves between said rib-like portions at the inner side of the conduit so as to strengthen the conduit against lateral strains applied to the said exterior loop bights and also presenting a clear non-interrupted raceway throughout the length of the conduit. 90

3. As a new article of manufacture, a fabric single walled conduit characterized by exterior annular rows of loop bights, with the bights in one row about the conduit extending in an opposite direction to the bights in the next adjacent rows to render the conduit highly flexible and provide radially extending interstices between all of said loops, said fabric also characterized by interior longitudinal rib-like portions with longitudinal grooves between said rib-like portions at the inner side of the conduit so as to strengthen the conduit against lateral strains applied to the said exterior loop bights and also presenting a clear non-interrupted raceway throughout the length of the conduit, and a coating substance impregnating the fabric and filling the said interstices between 100 said loops. 110

4. As a new article of manufacture, a tubular knitted conduit having staggered interstices on the exterior and longitudinal ribs on the interior producing longitudinal 125 grooves, said interstices being filled with a stiffening and finishing compound.

5. As a new article of manufacture, a tubular knitted conduit characterized by relatively deep external pockets or inter- 130

stices, and internal contacting ribs forming braces against external pressure.

6. As a new article of manufacture, a tubular knitted conduit characterized by 5 substantially parallel internal ribs contacting with each other throughout the circum-

ference and acting as braces against external pressure.

In testimony whereof we affix our signatures.

VICTOR C. GILPIN,
JOHN E. McAULIFFE.
